UNITED STATES PATENT OFFICE.

JOHN HOWARD TABLER, OF LANHAM, MARYLAND.

BUCKLE.

1,264,996.

Specification of Letters Patent.

Patented May 7, 1918.

Application filed March 10, 1917. Serial No. 153,951.

To all whom it may concern:

Be it known that I, JOHN HOWARD TABLER, a citizen of the United States, residing at Lanham, in the county of Prince Georges 5 and State of Maryland, have invented a Buckle, of which the following is a full and complete specification.

My invention relates more especially to that particular type of buckle in which the 10 free end of the attached strap or webbing is connected and secured to the front end of said buckle by frictional engagement therewith, leaving the strap free of the usual holes and permitting it to be readily and 15 accurately adjusted or tightly bound around the article to which it may be applied; being in the present instance an improvement upon the buckle shown and described in my prior Patent No. 1,216,881, issued February 20th, 20 1917.

The primary object of my invention is to provide a tongueless buckle of this general type for use in connection with a webbing-strap for general purposes, whereby 25 the strap may be easily and conveniently looped around a package, school books, &c., and the slack quickly taken up by simply pulling upon the free end of the same; the engagement of the cross-bars of the buckle 30 with the ends of the strap coöperating in the present instance to firmly hold down the front end of the buckle and provide a more secure binding action on the free end of the strap which is looped therein, preventing 35 said binding strap from becoming loose under the tension to which it may be subjected in use.

These objects and advantages, as well as others that will hereinafter appear, are attained in the present instance by the particular formation of the buckle comprising 40 opposite side pieces and a plurality of cross-bars extending between the same and arranged in a particular manner to provide 45 for connecting the ends of the webbing-strap thereto in an effective manner, all as herein-after fully described and specifically claimed.

In the accompanying drawings, forming a part hereof:

50 Figure 1 is a perspective view illustrating

the application of my improved buckle in connection with a book strap.

Fig. 2 is a sectional view of the buckle, in connection with a webbing strap.

Fig. 3 is a plan view of the buckle. 55

Fig. 4 is a view illustrating a modification hereinafter referred to.

Like numerals of reference indicate like parts in all the figures of the drawings.

In carrying out my present invention the 60 buckle is made of a single casting or in one piece to present opposite parallel side pieces 7, 7, and a plurality of cross-bars, herein-after referred to, extending between said side pieces and providing the special means for 65 connecting both ends of the webbing-strap, as A, thereto.

Extending between the side pieces 7, a short distance from the rear end of the buckle, and at the upper edges of said side 70 pieces, is a cross-bar 8, to which one end of the webbing-strap A is attached either temporarily or permanently, as hereinafter described, and adjoining said cross-bar in the rear thereof is a cross-bar or cross-piece 75 9, below which the attached end portion of the strap passes so that said cross-bar or cross-piece will act as a stop, for the purpose which will be hereinafter explained.

At the forward end of the buckle is a 80 cross-bar 10, extending between the side pieces 7 preferably a short distance above the lower edges thereof, and this cross-bar may be provided with an angular edge 11 at the inner lower corner thereof, as shown in 85 Fig. 2. Said front cross-bar 10 is provided with a forwardly-projecting tongue 13, providing the means by which the front end of the buckle may be tilted upward in releasing the strap. 90

In the rear of the front cross-bar 10 and at a higher elevation than the same is a cross-bar 15, also extending between the side pieces and disposed with relation to said front cross-bar so as to leave a narrow space 95 or slot, as 16, through which the end of the strap is passed after being looped over the cross-bar 15 from the rear thereof. As in my prior patent hereinbefore mentioned the cross-bars 10 and 15 form the means for 100

connecting the free end of the strap to the buckle so that it will be adjustable therein for binding said strap around the package, and although the front cross-bar is preferably located above the lower edges of the side pieces this is not essential in the present instance, and likewise the companion cross-bar 15 may be located at a greater or less distance from said front cross-bar according to the thickness of the webbing used and extent of the frictional engagement required.

The buckle is intended for use in connection with a strap of leather, fabric, or other material possessing the required flexibility, and in practice I find it very effective with a cotton strap, commonly known as webbing, the width of the strap approximating the space between the side pieces of the buckle so as to easily slip therebetween; the buckle being made of different sizes according to the different width of strap or webbing that may be produced; for instance when used as a buckle in connection with a book-strap the latter may be of three-quarter-inch webbing and the width of the buckle between the side pieces thereof should correspond, and when applied to a trunk-strap the webbing would probably be an inch and a half or two inches wide according to the work or strain to which the strap and buckle may be subjected, the size and strength of the buckle corresponding, of course, with the width and thickness of webbing used.

In attaching the buckle permanently to a length of webbing-strap one end of the latter is attached to the cross-bar 8 by looping it around said cross-bar and riveting the terminal portion to the body directly below the same, so that this attached end of the strap will pass out of the rear end of the buckle below the rear cross-piece 9, as shown in Fig. 2 of the drawings. In attaching a cotton webbing strap to the buckle the end of the strap is turned in (Fig. 2), so that it will not fray, requiring three thicknesses of the webbing adjoining the cross-bar 8, which lie under the cross piece 9; and therefore in practice said cross-piece is preferably located a distance above the lower edges of the side pieces 7, 7, to receive the several thicknesses, with probably a single thickness below said edges.

In use the free end of the webbing-strap is passed into the forward end of the buckle below the cross-bar 10, up between the cross-bars 8 and 15, over the last mentioned cross-bar to and under the front cross-bar, so that said free end of the strap will be looped in the buckle and the terminal portion pass out of the same between the front cross-bar and body of the strap. The strap is then formed into a loop, (see Fig. 2) which may be readily slipped over the package or pile

of books and tightly bound around the same by simply pulling on the projecting end of said strap. Of course the threading of the free end of the strap, or looping it around the cross-bar 15, may be done after the strap is passed around the package or books; but by keeping the adjustable end of the strap in looped engagement with the cross-bar 15, or in a more convenient operative position as shown in said Fig. 2, it may be more quickly manipulated in binding or tying up packages, books, &c.

When the free or projecting end of the strap is pulled upon in binding the package the looped portion of the strap within the front end of the buckle is frictionally engaged in such manner as to prevent any giving or loosening under the strain on that portion of said strap which encircles the package; this binding action of the front part of the buckle being augmented to a considerable extent by reason of the co-operation of the cross-piece 9 at the rear end of said buckle bearing upon the attached end of the strap and holding the forward end of the buckle down preventing movement thereof away from the package. The application of the cross-piece or stop-bar not only maintains the binding action of the buckle on the adjustable end of the strap but by holding the front end of the buckle down keeps the buckle flat on the package so that it will present a neat appearance.

In order to release the binding action of the buckle on the strap it is only necessary to tilt said buckle upward by pushing a finger of the hand under the lifting-tongue 13, which relieves the binding action of the front cross-bar 10 and permits the looped end of the said strap to slip around the companion cross-bar 15.

For convenience in holding the buckle while pulling on the projecting free end of the same, and more especially as a finger-hold for carrying the package, I may form at the rear end of the buckle, preferably integrally with the cross-piece 9, a ring 17, as shown in the modification Fig. 4 of the drawings. The utility of this ring will be readily apparent, and it will be found especially useful to letter-carriers when the strap and buckle are employed for tying together packages of mail-matter.

Having described my invention, I claim:

A buckle comprising side pieces with lower straight bearing edges, a front cross-bar at the upper edges of the side pieces having a forwardly-projecting lifting-tongue, a plain cross-bar in the rear of the front cross-bar at a higher elevation than the same over which the free end of the strap is looped to pass under the front cross-bar and lifting-tongue, a plain cross-bar near the rear ends of the side pieces

at the upper edges thereof to which the other end of the strap is attached, and a cross-piece extending between the side pieces above the lower edges thereof to bear upon the attached end of the strap and force the front cross-bar and lifting-tongue downward, whereby when the strap is un-

der tension the buckle will be disposed on a line with the portions thereof extending from said buckle front and rear and maintain frictional engagement with the looped end of the strap, as herein shown and described.

JOHN HOWARD TABLER.
